US0D1060206S

(12) **United States Design Patent** (10) **Patent No.:** **US D1,060,206 S**
Dunn (45) **Date of Patent:** **** Feb. 4, 2025**

(54) **SOLAR POWERED ELECTRONIC DISPLAY ASSEMBLY WITH POLE MOUNT**

H01L 31/0543; H01L 31/02013; H01L 31/1876; H01L 51/0061; H02S 40/34; H02J 3/38

(71) **Applicant:** **Manufacturing Resources International, Inc.**, Alpharetta, GA (US)

See application file for complete search history.

(72) **Inventor:** **William Dunn**, Alpharetta, GA (US)

(56)

References Cited

(73) **Assignee:** **Manufacturing Resources International, Inc.**, Alpharetta, GA (US)

U.S. PATENT DOCUMENTS

(**) **Term:** **15 Years**

(21) **Appl. No.:** **29/958,980**

(22) **Filed:** **Aug. 22, 2024**

Related U.S. Application Data

(60) Continuation of application No. 29/933,522, filed on Mar. 20, 2024, now Pat. No. Des. 1,046,762, which is a division of application No. 29/895,040, filed on Jun. 16, 2023, now Pat. No. Des. 1,025,882, which is a division of application No. 29/841,408, filed on Jun. 6, 2022, now Pat. No. Des. 993,909, which is a division of application No. 29/711,250, filed on Oct. 29, 2019, now Pat. No. Des. 958,059.

(57) CLAIM

The ornamental design for a solar powered electronic display assembly with pole mount, as shown and described.

DESCRIPTION

FIG. 1 is a front perspective view of the solar powered electronic display assembly with pole mount;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top view thereof;

FIG. 7 is a bottom view thereof; and,

FIG. 8 is an environmental view thereof.

The broken lines shown represent environmental subject matter and form no part of the claimed design. The dot-dashed broken line(s) define the bounds of the claimed design and form no part thereof.
